UNITED STATES PATENT OFFICE.

SAMUEL H. LEWIS, OF RICHMOND, VIRGINIA.

STEAM-SUPPLY MEANS FOR CYLINDERS OF RAILWAY-LOCOMOTIVES.

1,399,131.

Specification of Letters Patent.

Patented Dec. 6, 1921.

Application filed November 9, 1918. Serial No. 261,823.

To all whom it may concern:

Be it known that I, SAMUEL H. LEWIS, a citizen of the United States, residing at Richmond, in the county of Henrico and 5 State of Virginia, have invented certain new and useful Improvements in Steam-Supply Means for Cylinders of Railway-Locomotives, of which the following is a specification.

10 My invention relates to fluid pressure operated apparatus, for supplying steam to the cylinder or cylinders of a railway locomotive, when the main supply of steam is cut off therefrom, and the engine is drifting by gravity or inertia.

As is well known, railway locomotives are frequently operated with superheated steam, which is heated to a temperature of about 600° F. This high temperature steam heats 20 the walls of the cylinders of the engine to a high temperature, so that the oil is burned or flashed, upon the introduction of air, smoke box gases and cinders, into the cylinder or cylinders. This air, gas and cinders 25 are drawn into the cylinder or cylinders, when the main supply of steam is cut off, and the engine is traveling or drifting above a comparatively low speed, as partial vacuums are then ordinarily created within 30 the cylinders. It is obvious that the intake of air and the like into the cylinders may be prevented by the presence of a suitable amount of steam in such cylinders, when the main supply is cut off and the engine is 35 drifting.

An important object of the invention is to provide means for regulating the degree of pressure necessary to open the steam supply valve, whereby such valve will open 40 when the engine reaches a selected speed.

A further object of the invention is to provide adjustable yielding means to oppose the opening movement of the steam supply valve, whereby it may be set to open at a selected speed of the engine, without varying the volume of the control apparatus.

Other objects and advantages of the invention will be apparent during the course of the following description.

50 In the accompanying drawings forming a part of this specification and in which like numerals are employed to designate like parts throughout the same,

Figure 1 is a side elevation of apparatus 55 embodying my invention, showing the same applied to a railway locomotive,

Fig. 2 is an enlarged central vertical sectional view through the control apparatus, parts being shown in elevation.

Fig. 3 is an edge elevation of the body 60 portion of the control apparatus, taken at a right angle, to Fig. 2, with parts omitted.

Fig. 4 is a horizontal sectional view taken on line 4-4 of Fig. 3, with parts omitted, and,

Fig. 5 is a central vertical sectional view through a steam valve and associated means, parts in elevation.

In the drawings, wherein for the purpose of illustration is shown a preferred embodiment of my invention, the numeral 10 designates a railway locomotive of any well known or preferred type. This locomotive embodies a steam turret 11, as shown. The numeral 12 designates the cylinders of the 75 locomotive, each of which is provided with the usual steam chest 13, for connection with a steam supply pipe 14. There are two steam supply pipes 14, one for each cylinder, as is well known, which are connected with 80 the superheater. The steam chest 13 has the usual distribution valve operated by a radius rod 15 or the like.

Attention being called more particularly to Figs. 1, 2, 3 and 4, it will be seen that the 85 numeral 16 designates a control apparatus, as a whole, comprising a pressure chamber 17, which is preferably cylindrical, and vertically arranged. The control apparatus is rigidly connected with a horizontal arm 18, 90 which is rigidly secured to a bracket 19, attached to the guide yoke of the locomotive or other suitable part thereof.

At its upper end, the chamber 17 has a screw-threaded opening 20 receiving the 95 lower screw-threaded end of a preferably tubular plug 21.

The numeral 23 designates a partition or wall, forming a chamber 24 having at its upper end a vertical opening 25, in communication with a pressure supply pipe 26, as shown. This pressure supply pipe 26 leads to a tank 27, containing compressed air or other fluid pressure. At its lower end, the chamber 24 has communication with the 105 chamber 17, through the medium of a vertical port 28. At the upper end of the port 28 is a valve seat 29, engaged by a vertically movable valve 30, carried by a vertical depending stem 31. This stem projects 110 through a depending guide tube 32 and a stuffing box 33. A sliding sleeve 34 is aper-

tured for the reception of the stem 31 and is arranged within the lower end of guide tube 32. The lower portion of the stem 31 has a transverse opening for the reception 5 of a pin 35, contacting with the sliding sleeve 34. A compressible coil spring 36 surrounds the stem 31 and is confined between the end of the sleeve 34 and a gland 37, projecting into the stuffing box 33.

10 Arranged within the lower portion of the chamber 17 is a raised portion 38, having a vertical port 39, in communication with a receiver pipe 40, as shown. At the upper end 15 of the port 39 is a valve seat 41, engaged by a vertically movable valve 42, secured to a depending vertical valve stem 43. This valve stem extends through a tubular guide 44, and stuffing box 45. Surrounding the lower portion of the stem 43 is a sliding 20 sleeve 46, mounted to reciprocate within the lower portion of the tubular guide 44. The lower end of the stem 43 has a transverse opening formed therein for the reception of a pin 47, as shown. A compressible coil 25 spring 48 surrounds a portion of the stem 43, and is confined between the sleeve 46 and a gland 49.

Means are provided to alternately raise the stem 31 and 43, for opening the valves 30 carried thereby, such means comprising a swinging arm 50, provided at its upper end with a head 51, having an opening 52 formed therein, to pivotally receive a pin 53. This pin is carried by depending supports 54, 35 rigidly secured to the lower end of the depending tubular guides. At its upper end, the swinging arm 50 is provided with lateral extensions 55, having screw-threaded openings for the reception 40 of set screws 56 or the like. When the arm 50 is in the vertical position, the screws 56 are both slightly spaced from the lower ends of the valve stems, whereby both valves are closed and when the arm 50 is swung in 45 either direction the corresponding valve stem is elevated and the valve unseated. However, both valves cannot be open at the same time.

Pivottally connected with the lower end 50 of the arm 50 is a link 57, which is pivoted to the radius rod 15, or other movable part of the locomotive.

The receiver pipe 40 which leads into the vertical port 39 is also connected with fluid pressure operated apparatus, comprising a vertical cylinder 58, provided near its upper end with a port 59, leading to the atmosphere. Mounted to reciprocate within the cylinder 58 is an ordinary movable piston 60. This piston fits within the cylinder 58 in a manner to permit of the slight escape of fluid pressure between it and the wall of the cylinder, whereby this fluid pressure may pass to the atmosphere 65 through the port 59, but the escape of fluid 70 pressure is not sufficient to prevent the fluid pressure introduced into the lower end of the cylinder 58 from elevating the piston 60, in the proper operation of the apparatus. The piston 60 has a vertical stem 61 connected therewith. Further, the valves 30 and 42 must be alternately opened with sufficient speed to overcome the loss of pressure due to leakage through the port 59 to the atmosphere, and maintain a pressure 75 sufficiently high to hold the piston elevated. It is thus seen that the piston will be elevated and retained elevated, when the speed of the locomotive exceeds a predetermined degree, whereby the steam supply valve is 80 retained permanently open during such operation.

The numeral 62 designates a drifting supply pipe, the forward end of which is connected with branch pipes 63, by means of 85 a T-coupling 64. These branch pipes lead into the steam supply pipes 14. It is to be understood that the invention is in no sense restricted to this precise construction, as it is obvious that the forward end of the 90 pipe 62 may be connected in the steam passage between the main throttle valve and the locomotive cylinders. The pipe 62 has its opposite end suitably connected with the steam turret 11, but it is to be understood 95 that this pipe may be connected with any other suitable source of steam supply.

Connected in the pipe 62 is a valve structure including the casing 65, provided with a valve seat 66, having its opening covered 100 and uncovered by a vertically movable valve 67. The valve 67 is moved downwardly by a compressible coil spring 68 and also by the fluid pressure upon the unbalanced area of the upper end of the valve stem 61, to 105 which the valve 67 is rigidly secured. The stem 61 operates within a guide 69. The guide 69 is cylindrical and externally screw-threaded, for receiving thereon an adjusting nut 69', which engages with the spring 110 68. It is obvious that by rotating this nut 69' the tension of the spring 68 may be varied, thereby causing the valve 67 to open, upon the supplying of a different degree of pressure within the cylinder 58, beneath the 115 piston 60. Any steam passing from the casing 65 about the stem 61 through the guide 69, discharges to the atmosphere through the port 59. It is obvious that as the valves 30 and 42 are alternately opened 120 and closed, fluid pressure is intermittently fed into the receiving pipe 40 and hence passes to the cylinder 58. As the speed of the locomotive reaches a predetermined point, the pressure within the cylinder 58 125 is built up sufficiently to elevate the piston 60, and retain the same elevated during the travel of the locomotive at or above the selected speed, the valve 67 being retained open. It is thus apparent that by turning 130

the nut 69', the tension or stiffness of the spring 68 may be increased or decreased, thereby changing the speed at which the valve 67 will open. In my co-pending application for steam supply means for cylinders of railway locomotives, filed July 20, 1918, Serial No. 245,936, the selected speed of the locomotive at which the valve 67 would open, was obtained by varying the volume of the casing of the control apparatus. By securing tubes of different lengths to the casing of the control apparatus, its volume could be increased or decreased. In this way the valve 67 would open at different selected speeds. By the present construction, I am able to dispense with the employment of these tubes of different length and accomplish the same result, by regulating the tension of the spring 68.

20 The operation of the apparatus is as follows:

When the locomotive is traveling with the main throttle valve partly or wholly open the steam as supplied to the cylinders 12 through the steam pipes 14, as is well known. The reciprocatory movement of the rod 15 swings the arm 50 to alternately open one valve 30 and close the other valve 42. When the rear valve 30 is open, compressed air passes from the tank 27 through pipe 26 into the pressure chamber 17, but cannot pass therefrom as the forward valve 42 is closed. When the forward valve 42 is open the rear valve 30 is closed, whereby the fluid pressure within the chamber 17 discharges into the receiver pipe 40 and the lower end of the cylinder 58. This introduction of pressure within the cylinder 58, when it rises to a required degree, causes the piston 60 to rise, thereby opening the valve 67. The fluid pressure can slightly escape around the piston 60, but the pressure is intermittently supplied from the chamber 17, sufficiently rapidly, when the locomotive is traveling above a predetermined speed, to retain the piston elevated and the valve 67 permanently open, and the steam from the turret 11 passing through the pipe 62 will discharge into the steam pipes 14, and hence into the cylinders 12. The steam is fed through the pipe 62 into the cylinders 12 when the throttle is closed, in proper amounts to prevent the formation of vacuums therein. This prevention of the formation of vacuums within the cylinders and the exclusion of air and the like therefrom prevents the destruction of the lubricant. The steam also serves to lubricate the cylinders.

Particular attention is called to the fact that the opening or closing of the valve 67 is in no way dependent upon the creation of vacuum within the cylinders, as by the employment of my apparatus, it is impossible for vacuums to occur.

When the speed of the locomotive becomes lower than is required to maintain fluid pressure in the receiver pipe 40 and cylinder 58 at the degree required to hold piston 60 and valve 67 elevated, the piston 60 will be forced downward by the spring 68 and the action of the steam upon the unbalanced area of the upper end of the valve stem 61, and the valve 67 will be seated. This cuts off the supply of steam through the pipe 62 to the cylinders. When the locomotive comes to a stop, one or both of the valves 30 and 42 are closed, thereby entirely cutting off supply of fluid pressure to the cylinder 58 beneath the piston 60.

It is to be understood that the form of my invention herewith shown and described is to be taken as a preferred example of the same, and that various changes in the shape, size, and arrangement of parts may be resorted to without departing from the spirit of the invention or the scope of the subjoined claim.

Having thus described my invention, I claim:

In apparatus of the character described, a conduit to supply steam to the cylinder or cylinders of a railway locomotive, a valve casing arranged in said conduit, a valve in said casing to control the passage of steam through the conduit, a cylinder arranged near the valve, a sleeve in said cylinder forming a guide, a piston mounted to reciprocate within the cylinder having a stem reciprocable within said guide and connected with the valve to move it, a spring surrounding said stem and guide and engaging the piston to oppose its movement in the direction in which said valve is opened, a nut mounted upon said sleeve and adjustable thereon to regulate the tension of the spring, and a control apparatus operated by a movable part of the locomotive and serving to supply fluid pressure to the cylinder in quantities varying directly with the speed of the locomotive.

In testimony whereof I affix my signature in presence of two witnesses.

SAMUEL H. LEWIS.
